EXHIBIT 284

NO. 14,617

FEB 5, 1884

8999

8999

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 14,617, dated February 5, 1884.

Application filed December 26, 1883. Term of patent 3½ years.

To all whom it may concern:

Be it known that I, CATHERINE O'HARA, of the city, county, and State of New York, have invented and produced a new and original Design for a Pattern of a Lady's Walking-Skirt, (numbered 8,999;) and I do hereby declare that the engraved prints accompanying this specification convey to any one accustomed to using paper patterns a clear understanding of how a garment made up by the pattern will appear.

The design shows a round walking-skirt, a deep front drapery that is shaped in deep tabs at its lower edge, and displays three clusters

of plaits crossing from the back edges and tackings at the center, and a deep back drapery that exhibits draping plaits in its front edges and loopings at the center.

What I claim as my invention, and desire to secure by Letters Patent, is—

The design for a lady's walking-skirt, as shown in the engraved prints accompanying this specification.

CATHERINE O'HARA.
